[57] CLAIM

The ornamental design for a multi-tiered stand, as shown and described.

DESCRIPTION

FIG. 1 is a top, front and left perspective view of a multi-tiered stand showing my new design;

FIG. 2 is a front elevational view thereof;

FIG. 3 is a bottom plan view thereof;

FIG. 4 is a rear elevational view thereof;

FIG. 5 is a right side view thereof;

FIG. 6 is a left side view thereof;

FIG. 7 is a bottom perspective view of a shelf of the multi-tiered stand, shown separately for clarity of illustration, showing the vertical posts of the multi-tiered stand positioned therein when the multi-tiered stand is disassembled;

FIG. 8 is a top perspective view of the shelf of FIG. 7;

FIG. 9 is a bottom perspective view of the shelf of the multi-tiered stand, shown separately for clarity of illustration;

FIG. 10 is a top perspective view of the shelf of FIG. 9;

FIG. 11 is a bottom perspective view of a shelf of the multi-tiered stand, shown separately for clarity of illustration; and,

FIG. 12 is a top perspective view of FIG. 11.

The shelves shown in FIGS. 7-12 may be used in any number and arrangement within the claimed multi-tiered stand.
